CLINTON G. WILDERSON AND ELMER HARROLD, OF LEETONIA, OHIO, ASSIGNEES TO
THE CRESCENT MACHINE COMPANY, OF LEETONIA, OHIO, A CORPORATION OF
OHIO.

WOODWORKING-MACHINE.

1,088,501.

Specification of Letters Patent.

Patented Feb. 24, 1914.

Application filed December 1, 1910. Serial No. 595,093.

To all whom it may concern:

Be it known that we, CLINTON G. WILDERSON and ELMER HARROLD, of Leetonia, Columbian county, Ohio, have invented a new and useful Improvement in Woodworking-Machines, of which the following is a full, clear, and exact description, reference being had to the accompanying drawings, forming part of this specification, in 10 which—

Figure 1 is a front view of one form of our improved machine. Fig. 2 is an end view thereof. Fig. 3 is a plan view. Fig. 4 is a side elevation of a cover for the saw.

15 This invention relates to wood-working machines, and is designed to provide a machine on which various kinds of work can be done on the same piece without changing the machine.

20 A more particular object is, to provide a machine which is particularly adapted for small shops which do not have sufficient use for various types of machines to permit the installation of a machine tool for performing each of the different operations, such as planing, sawing, boring, rounding the edges of the poles, or shaping the edges of molding or similar articles.

The precise nature of our invention will 30 be best understood by reference to the accompanying drawings, which will now be described, it being premised, however, that various changes may be made in the details of construction without departing from the 35 spirit and scope of our invention, as defined in the appended claims.

In the drawings, the numeral 2 designates the frame of a jointer; 3 the shaft and 4 a driving pulley rigidly connected to the shaft 40 and adapted to receive the usual driving belt.

5 is the jointer table, which is arranged to be elevated and lowered by the adjusting screws 6.

45 Connected to the central portion of the shaft 3, is a jointer cutter 7; and connected to one end of the shaft is a chuck 8, arranged to receive any one of various tools, such as a bit 9. 10 is a saw mounted on the 50 other end of the shaft, as clearly illustrated in Figs. 1, 2 and 3.

Connected to one side of the machine is a bracket 11, which is provided with a guide for receiving a frame 12 on which is slidably mounted a table 13 for supporting the

material to be bored by the bit 9. 14 is a bracket secured to the other side of the main frame and having guides 15 for receiving the yoke 16, as illustrated in Figs. 1 and 2. Extending outwardly from the lower portion of this bracket 14, is a lug 17 which is screw threaded to receive the adjusting screw 18, adapted to raise and lower the yoke 16. The central portion of this yoke member, between the guides 15 is slotted as shown at 19, for the reception of a clamping screw 20 which extends into a screw threaded portion of the bracket 14, and is arranged to clamp the yoke 16 in its adjusted position in said bracket. Mounted on the upper portion of this yoke 16, is a saw table 21 to which is connected a bracket 22, arranged to adjustably receive the guide 23 for the material to be sawed.

24 is an adjustable guide above the table 75 5 for guiding the work for the jointer.

The device shown in Figs. 1 to 3 is arranged to permit a board to be run over the jointer edgewise to square up an edge with relation to the broad faces thereof, after which it is passed to the saw table, and the proper width of strip cut therefrom. The strip is then run over the knife of the jointer to surface the rough edge left by the saw. By adjusting the guide 23, strips of various sizes can be cut from the board. By this arrangement, we are able to square up the board from which the strip is to be cut, then cut the strip the proper width and then surface the rough face and turn out a finished 85 article on the same machine.

21^a designates orifices in the saw table 21 which are arranged to receive pins 25 extending downwardly from the lower face of a saw guard 26. This guard may be placed 90 above the saw to completely cover it when the saw is not in use, and thereby prevent any one from being injured by the saw.

It will readily be understood by those familiar with the art that various tools other than a saw can be secured to the shaft 3, and that yokes of different shapes than the one shown can readily be secured to the side of the frame of the machine, and to which various work-holding devices may be secured to meet the various requirements of the work to be done.

The advantages of our invention result from the provision of a machine which is adapted to perform various operations on 110

one piece of work without removing any of the parts. Further, from the provision of a machine which is adapted to be readily changed to enable it to perform further operations on the piece.

5 We claim:—

1. A wood-working machine, having a main frame, a shaft rotatably journaled in said frame, vertical guides on the side of the frame below the shaft, a yoke slidably mounted in said guides and having arms extending upwardly on each side of the shaft, and a work guide above said shaft connected to the yoke arms; substantially as 10 described.

2. A wood-working machine, having a main frame, a shaft rotatably journaled in said frame, vertical guides on the side of the frame below the shaft, a yoke slidably mounted in said guides and having arms 15 extending upwardly on each side of the shaft, and a work guide above said shaft connected to the yoke arms, together with 20

a screw device for adjusting the yoke, and means for securing the yoke in its adjusted 25 position; substantially as described.

3. An attachment for wood-working machines, comprising a guide member arranged to be secured to the side of a wood-working machine, a yoke slidably engaging said 30 guide, said yoke having upwardly and outwardly extending arms, a work guide connected to the upper ends of said arms, there being a slot in said yoke below the arms, and a securing screw extending through said slot 35 and having a screw threaded engagement with a guide member; substantially as described.

In testimony whereof, we have hereunto set our hands.

CLINTON G. WILDERSON.
ELMER HARROLD.
